METHOD OF AND MOLD FOR CASTING PISTON RINGS

Filed Dec. 20, 1926

UNITED STATES PATENT OFFICE

ERNEST N. BRODERICK AND THEOPHEILES D. LUCIER, OF DETROIT, MICHIGAN

METHOD OF AND MOLD FOR CASTING PISTON RINGS

Application filed December 20, 1926. Serial No. 155,845.

This invention relates to the casting of piston rings, its principal object being to provide an improved method of producing castings in quantities whereby the metal in each 5 completed ring will be substantially free from strains, cementite, sand holes, blow holes and other imperfections common to still poured metal and operable to produce undesirable distortion therein when the ring 10 is machined or in its subsequent use.

Further objects of the invention are to provide a method of casting rings of the type shown in a copending application, Serial No. 421,893, filed November 5, 1920 (since patented July 12, 1927, No. 1,635,530), in which a ring is described having certain of its surfaces provided with a hard, elastic and unbroken scale; except at the point at which the ring is split, in order to maintain the warping stresses normally present in a cast ring inactive to a degree rendering the said ring proof against such warping after casting and machining; and to obtain a casting which may be machined to meet the usual requirements of a piston ring and having such scale protected walls in addition to a softer wall on its outer periphery after machining.

Still further objects of the invention are to provide a method of producing annular castings having great homogeneity of metal throughout the casting and in which any excess of metal and any loose material within the mold will be carried out of the mold; and to provide means ensuring the compression of metal in the molds during casting by resisting the release of overflow from the molds.

Still further objects subsidiary to and resulting from the above objects, or from the construction or operation of the invention as it may be carried into effect, will become apparent as the said invention is hereinafter further disclosed.

When iron is cast within a mold, the surface in contact with the mold is generally harder than the metal within the interior of the casting. This is partially due to the chilling of the surface layer by contact with the relatively cooler mold surface, and if 50 sand molds are used, is partially due to parti-

cles of molding sand entrapped within the surface layer during the setting of the metal. Or if the sand mold be well made and protected, this sand entrapping may be practically negligible but the oxidizing and chilling 55 of the surface will still produce a characteristic hard surface layer. This harder surface is hereinafter referred to as the "scale". When piston rings are individually cast, the common practice has been to remove the scale 60 of the cast iron from the top and bottom of the ring from its outer periphery, as well as to remove adhering masses of metal or sprues from the interior periphery of the ring. This adhering metal may form a portion of 65 the ingate by which the metal has entered the mold or may be formed by the overflow in the molding process as will be well understood by those acquainted with the art to which the invention appertains. 70

When this internally extending metal is broken or cut away from the inner periphery of the ring, the scale of the inner periphery thereof is also broken as a natural consequence, and this scale is very desirable in an 75 unbroken condition due to the fact that it will effectively counteract warping stresses in the ring, a ring so treated is readily deformed; so that it is evident that if uniformity of spring tension in the ring is to be secured it must be so cast that no sprues or 80 projections requiring removal must be formed on its inner periphery. These remarks also apply to the top and bottom of the ring upon which an unbroken circle of 85 scale is very desirable for similar reasons.

An important feature of our invention is the securing of the elimination of sprues or projecting masses of metal upon the inner periphery of the ring or upon the top and 90 bottom of the ring adjacent such inner periphery. Metal is driven by centrifugal force through an ingate into and around each of a series of annular spaces in a rotating mold to an outgate, and the said ingate and 95 the outgate orifices are connected to each of the annular spaces forming the ring molds at proximate to their outer peripheries so that the sprues will remain attached to the outer edges of the ring blanks. These edges are 100

preferably formed with an annular rim adapted to be cut away in finishing the rings. It will thus be evident that an inner U-shaped scale forming the inner periphery of the finished ring and the adjacent portions of the top and bottom thereof will be left substantially intact and free from any interruptions or breaks such as result from the removal of sprues formed in the ordinary processes of casting.

The invention is more particularly described and ascertained hereinafter by way of example, having reference to the accompanying drawing, wherein,—

15 Figure 1 is a vertical section through a preferred form of mold adapted for the carrying out of the said invention, the said section being taken on the line I—I of Figure 3;

20 Figure 2 is a vertical section at right angles to that of Figure 1 taken on the line II—II of Figure 3;

Figure 3 is a horizontal section through the mold on the line III—III of Figure 1;

25 Figure 4 is a perspective view, partly broken away, illustrating a pair of piston ring blanks produced by the process;

Figure 5 is a transverse section of such blank showing the nature of the connection 30 between the two rings, and

Figure 6 is a section on the line VI—VI, Figure 5.

Similar characters of reference indicate similar parts in the several figures of the 35 drawing, and Figure 4 is drawn to a larger scale than Figures 1, 2 and 3, and Figures 5 and 6 to a larger scale than is Figure 4.

In the said drawing, there has been shown a form of mold suitable for carrying out of 40 the present process, and the production of ring castings of the type described in our application for Letters Patent Serial No. 421,893, though it will be understood that the invention is not limited to the precise details 45 of the mold herein shown, since it will be apparent that the design of the molds may be varied to suit different requirements without departing from the essential features of the process herein described.

50 1 indicates a rotatable driving shaft upon which is mounted a head 2 provided with arms 3 bearing posts 4 secured thereto by nuts 5, the upper ends of the said posts receiving a yoke 6 which is bored to provide an 55 internally tapered shoulder 7. This shoulder 7 is adapted to bear against an external tapered shoulder 8 of an annular rib 9^a formed on a two-part casing, the parts 9 and 10 of which together form a vertically c) parted cylinder. The lower end of the cylinder rests on a circular table 11 provided with a casing-engaging flange 12 and a boss 13 which nests in the upper end of the head 2. The yoke 6 forms a clamping means for the 65 two parts of the cylindrical casing, as will

be readily seen from the drawing, and the top of the casing is preferably enclosed except for a central opening 10^a provided therein.

Although it is possible to cast rings singly by our process, as will be readily understood, for the purposes of economy it is preferred to cast the rings in plurality or gangs, the said process being particularly adaptable to such form of production; and in the drawing we show an arrangement whereby the 75 upper rings are gated in pairs and the lower ones in quadruple although the number of rings which may be gated together is only limited by the peculiarities of molding which are well known to those skilled in this art. 80

To carry out our process with the device under consideration, we provide a core 16 which has formed therein ring channels 16^a of a T configuration in cross section, the outer parts of which channels are enlarged to form 85 annular recesses 16^b, the purpose of which recesses is hereinafter described, and this core is surrounded by a two-part lining 14, 15 within the cylindrical casing 9, 10. To give access to and egress from the said channels 16^a gates 16^c and 16^d are provided in the form of grooves in the core extending between the marginal recessed parts 16^b of the said channels.

The core 16 is provided with a central 95 pouring orifice 17 located beneath the opening 10^a in the top of the cylindrical casing, and extending radially from this orifice 17 are ingate openings 18, 19, 20, 21 and 22 communicating with the grooves forming the 100 gates 16^c in the core and incidentally with the associated annular channels in the said core; and on the opposite side of the core outlet openings 24, 25, 26, 27 and 28 are provided leading from the grooves forming the gates 105 16^d and extending radially inward thereof to a riser 30 formed in and extending longitudinally of the said core. This riser is preferably formed with an off-set enlarged channel 34 the purpose of which is hereinafter 110 explained. The table 11 is also provided with an outlet opening 32 contiguous to the foot of the riser 30.

The device described is intended to be rotated rapidly on or by the shaft 1, during 115 which rotation molten metal is poured through the opening 10^a into the orifice 17 of the core and is centrifugally driven through the ingate openings 18, 19, 20, 21 and 22 and through the gate grooves 16^c into the channels 16^a until the said channels are filled with the molten metal, whereupon the said metal commences to extrude through the openings 24, 25, 26, 27 and 28 toward or into the riser 30.

The said outlet orifices are somewhat restricted or of smaller capacity than the inlet orifices so that, upon the centrifugal action referred to being brought into effect and the channels being filled with molten metal, the 130

compression of the same metal within the said channels is effected due to the centrifugal force and also to the restriction of the outlets from the said channels so that a very compact casting may be secured; and, furthermore, due to the radiating direction of such force the heavier metal is driven into the channels and the lighter impurities displaced thereby from the channels, such impurities finding their way through the radial 5 openings and thus freeing the castings therefrom.

An economy of metal is also secured due to the positive filling of the channels irrespective of the complete filling of the central 15 orifice 17 as it will be realized that sufficient metal may be poured into the revolving mold to fill the said channels and wholly or partly fill the gates and inlet and outlet orifices without requiring the provision of excess 20 metal in the central pouring orifice. This orifice 17 is preferably tapered upwardly as shown so that the centrifugal whirlpool action of the metal will effect its flow over the walls of the said orifice and ensure the result 25 last referred to.

In practice it has been found that very efficient castings can be produced leaving only a thin film of metal on the walls of the said orifice 17 which film is usually found to contain the impurities displaced by the forces 30 acting upon the metal in the channels and to be perforated by the gases occluded from such metal in the channels.

Figure 4 illustrates a casting so produced 35 wherein it will be seen that the rings 35 as cast are provided with upper and lower peripheral ribs 35^a and 35^b, respectively, formed by the recesses 16^b of the channels 16^a, and that the rib 35^a of the lower ring is connected 40 to the rib 35^b of the upper ring by means of gate members 36 and 36^a formed by the grooves 16^c and 16^d of the said core, from which gate members sprues 37 and 37^a, 45 formed by the inlet and outlet openings of the said core extend. It will also be seen, especially from Figure 5 and Figure 6, that the said gate members connect with the said ribs 35^a and 35^b solely so that the ring castings 50 are provided with surfaces 35^c, 35^d and 35^e, the scale of which is unbroken upon the severing of the gate members 36 and 36^a from the rings when the said rings are separated.

The completion of the rings after separation 55 is effected by the machining off of the ribs 35^a and 35^b together with the machining of the outer peripheral face of the said rings, and it will be obvious that after such machining the scale is unbroken on the inner periphery 35^d of the rings and that the scale surfaces 35^c and 35^e will also remain unbroken. Consequently, when the ring is parted at any 60 point as is usual in piston rings this scale forms means positively counteracting internal stresses in the rings which would other-

wise result in their warping and consequent reduction of their efficiency.

The riser 30 is shown as being provided with a tangentially disposed chamber 34 which receives excess metal from the outlet 70 openings 24, 25, 26, 27 and 28, so that such excess metal becomes detached from the metal in such openings and prevents connections being established between the entire number of channels as might otherwise occur in which case shrinkage losses transmitted throughout the rings might seriously warp the castings where a large number were being made. 75

40 indicates reinforcing members extending upwardly through the core 16 to ensure 80 it against any relative movement or distortion in the lining 14, 15, and may be used according to necessity or desirability.

In producing piston ring structures in this 85 particular way, not only is it possible to produce the final casting in such way as to provide the skin effects on the final product heretofore pointed out, but, in addition, the particular method employed in casting ensures that the body of the ring itself will be of a 90 homogeneous texture throughout, a condition that is more or less difficult when casting by centrifugal action.

This will be readily understood by considering the conditions set up in the structure 95 shown in Fig. 4, which presents a perspective view of one of the pairs of rings which are cast in the mold of the remaining figures, and in which the part 37 may be considered as the inlet sprue and 37^a the outlet sprue, the former being produced in the gate leading 100 from the supply, while the latter sprue is the metal in the gate opening into the channel 30.

As will be understood the centrifugal force 105 is active in both of these gate, being greater in effect in the inflow gate than in the outflow gate, since the former is not only larger in cross-sectional area, but in the inflow gate the body of metal of the supply is being forced outwardly by this action so that there is the force provided by this larger body acting to force a flow of metal into the cross-connections 36; outward pressure is also active in the outflow gate, but here the gate is of less length, and there is no 110 body of metal present in channel 30 to produce the additional force that is present in the inflow gate, the excess metal being carried into the enlargement 34 by the action of the centrifugal force. Hence, the centrifugal action in the outflow gate serves to set up a counter pressure to the flow of metal toward the outlet, but the value of this pressure is less than that present in the inflow gate. As a result, 115 it will be evident that a flow of metal will be had from the inflow to the outflow, with the flow rate dependent on the differential between these forces.

In this condition of a flow of metal the 120 casting of the rings in pairs or multiples and 125

the use of the cross connections 36 and 36^a is of importance. This will be understood from the fact that the cross-connections have their outer face coincident in plane with the outer face of the rings and therefore have the same centrifugal force value as is present in the rings themselves, and also to the location of the cross connections.

- As will be understood, the radial flow of metal is in a direction such as to be entirely outside of the ring cavities, so that there is no radial pressure present within the said cavities other than is set up by the thickness of the cavities, the additional pressure being placed on the metal in the cross-connections. Hence, the flow of metal within the ring cavities is not materially disturbed by the centrifugal force, the latter tending to produce an equal pressure within the ring cavities. But this condition, as an aid to the homogeneous texture is amplified by the fact that the flow of metal to the ring cavities is lateral and in the plane of the ring, with the same character of action present at the outlet of the ring cavities into the cross-connections, the opposing streams of metal which meet at such outlet, not meeting as the end of a path of movement, but coming together and providing the lateral flow through the outlet into the cross-connection, so that the juncture is made of a flowing metal instead of a static metal, the counter pressure preventing a too rapid flow and thus ensuring that the texture at both the entrance to and outlet from a ring cavity will be similar to that of the remainder of the ring, and preventing the production of any blow-holes, etc., through trapped air, etc., the latter being driven out ahead of the flowing metal.
- In other words, the arrangement establishes a flow-path for the metal with an intermediate portion of the flow path divided temporarily into individual paths in which the desired article is produced, and with the opposite ends of the flow-path in the form of these cross-connections which form the entrance and exit of metal to and from the divided paths, and which are subjected to the radial pressures of differential values.
- One advantage in this respect is the fact that because the result is obtained by a flow of metal in this way, the length of time the mold is rotated to produce the centrifugal action is not required to be so accurately gaged, assuming a sufficient amount of metal is present. As will be understood, an excess period of rotation does not change the texture conditions, since the metal will continue to flow while the rotation continues, with the result that a greater amount of excess metal will pass through the outlet as the rotation is continued beyond that which would be normally required. Assurance can thus be had of a complete and proper casting operation, since the presence of the excess will indicate that

the ring cavities are properly filled and will remain so as long as there is metal present in the supply to set up the major pressure of the differential in pressure.

What we claim is:

1. A mold for casting piston rings comprising a core having an annular channel formed therein and a pouring orifice formed within said channel, said channel having marginal extensions, and gates connecting said orifice exclusively with said marginal extensions.

2. A mold for casting piston rings comprising a core having an annular channel formed therein and a pouring orifice formed within said channel, said channel having marginal extensions, and gates connecting said orifice exclusively with said marginal extensions, said gates having a depth not greater than the width of said marginal extensions at the point of connection therewith.

3. A mold for casting piston rings comprising a core having an annular channel formed therein and a pouring orifice formed within said channel, a gate connecting said orifice with said channel, and an outlet from said channel, said outlet being restricted relatively to said gate in order to provide back pressure.

4. A mold for casting piston rings in multiple, comprising a core having a series of annular channels formed therein and a pouring orifice formed within the confines of said channels, gates connecting said orifice to said channels, outlets extending from said channels, a riser formed longitudinally of said core and connected to said outlets, said riser having an offset enlarged portion for the purpose described.

5. In the art of casting piston rings in multiple by centrifugal action, a rotatable mold having spaced ring-cavities connected by spaced connection cavities, a supply cavity, an outlet passage, a connection between the supply cavity and a connection cavity, and a second connection between the outlet passage and a second connection cavity, the ring and connection cavities being located in a zone of greater centrifugal pressure than the similar pressures of the supply cavity and the outlet passage.

6. A mold as in claim 5 characterized in that the location of the outlet passage is in a zone of greater centrifugal pressure than the similar pressure of the supply cavity.

7. A mold as in claim 5 characterized in that the outlet passage includes a lateral extension leading in the direction of greater centrifugal pressure.

8. A mold as in claim 5 characterized in that the outer face of a connection cavity is aligned with the outer face of the ring cavities which it connects.

9. In the art of casting piston rings in multiple by centrifugal action, a rotatable

5 mold having ring cavities spaced the maximum distance from the axis of rotation, the ring cavities of a multiple group being spaced apart and connected together at spaced points, the outer face of the ring and connection cavities being alined, a central supply cavity, a connection between the supply cavity and one of the connection cavities to provide an inflow gate for the metal to the 10 cavities, and an outlet passage for excess metal located intermediate a second connection cavity and the axis of rotation, said passage being connected with such second connection cavity by an outflow connection, 15 whereby a flow path is established between the supply cavity and the outlet passage with the ring and connection cavities located in a zone of centrifugal pressure greater than that of the supply cavity and the outlet passage.

10. A mold as in claim 9 characterized in that the outlet passage includes a lateral extension leading in the direction of greater centrifugal pressure.

11. In the art of casting piston rings or the like by centrifugal action, the process which consists in establishing a flow-path for the ring metal, the metal in said flow-path being subject to centrifugal action, said flow-path including an intermediate annular portion having the cross-section of the desired cast product, said annular portion having the maximum centrifugal force pressure applied uniformly as respects the direction of 20 length of the annular portion, the flow of metal to and from the annular portion being in directions lateral of the annular portion and having centrifugal force pressure of similar value to that of the annular portion of 25 the flow-path with the entrance to and exit from the annular portion open to the free passage of metal therethrough, said entrance and exit being substantially diametrically opposite each other relative to the annular portion, the ends of the flow-path extending substantially radial to the lateral portions of the flow-path, whereby the flow of metal through the entrance to the annular portion of the flow-path will freely divide and pass 30 in opposite directions toward the exit with the excess metal passing through the exit in a lateral direction into the exit end of the flow-path to complete the metal of the desired cast product intermediate to and connected with the metal of the lateral portions 35 of the flow-path at the conclusion of the centrifugal action.

12. A process as in claim 11 characterized in that the end of the outlet portion of the flow-path terminates at a greater distance from the axis of rotation of the flow path than the inlet end portion of such path, whereby the metal of the radial portion of the outflow will exert a counter pressure to 45 the discharging metal of less value than the

pressure exerted by the metal of the radial portion of the inflow of metal.

13. In the art of casting piston rings or the like in multiple by centrifugal action, the process which consists in establishing a flow-path for the ring metal, the metal in 50 said path being subject to centrifugal action, said flow-path including an intermediate portion temporarily divided to form individual paths within such intermediate portion, said individual paths being subjected to the maximum centrifugal force pressures and including the mold cavities of adjacent spaced-apart axially-alined ring cavities extending in parallelism, the undivided end portions of the flow-path being subject to centrifugal force pressures of less pressure value the outlet end portion serving to set up a counter-pressure activity, the individual paths being connected together at opposite 55 spaced points with the connections extending laterally between the paths in the zone of maximum centrifugal force pressure and forming the sections of the flow-path from and to which the individual paths lead.

14. A process as in claim 13 characterized in that the outlet end of the flow path terminates a greater distance from the axis of the individual paths than the entrance to the inlet end portion of the flow-path, whereby 60 the counter-pressure is of lesser value as a pressure source.

15. A process as in claim 13 characterized in that the outlet end of the flow path terminates at a greater distance from the axis 65 of the individual paths than the entrance to the inlet end of such flow-path, the outlet end portion terminating in a cavity zone leading laterally in the direction of greater 70 centrifugal force pressure, whereby the metal discharged from the outlet will be ineffective to increase the counter-pressure force of the outlet portion of the path.

In testimony whereof we affix our signatures.
